(57) **CLAIM**

The ornamental design for a vehicle mount as shown and described.

DESCRIPTION

FIG. 1 is a first perspective view of a vehicle dock; FIG. 2 is a second perspective view thereof; FIG. 3 is a bottom side view thereof; FIG. 4 is a top side view thereof; FIG. 5 is a first side view thereof; FIG. 6 is a second side view thereof; FIG. 7 is a rear side view thereof; and FIG. 8 is a front side view thereof. FIG. 9 is a first perspective view of a vehicle dock, wherein an access panel is in an open position; FIG. 10 is a second perspective view thereof; FIG. 11 is a bottom side view thereof; FIG. 12 is a top side view thereof; FIG. 13 is a first side view thereof; FIG. 14 is a second side view thereof; FIG. 15 is a rear side view thereof; and FIG. 16 is a front side view thereof. FIG. 17 is a first perspective view of a vehicle dock showing a tablet installed as environment; and, FIG. 18 is a second perspective view thereof. All other perspectives of this embodiment are as shown in FIGS. 1-8. In the drawings, the broken lines depict environmental subject matter only and form no part of the claimed design.

1 Claim, 18 Drawing Sheets
